Attorney.

UNITED STATES PATENT OFFICE.

PRATT C. MORRIS, OF THOMASVILLE, GEORGIA, ASSIGNOR OF ONE-HALF TO CHARLES W. COOPER, OF THOMASVILLE, GEORGIA.

AUTOMATIC SAFETY-SPRING AND BALL-VALVE COCK.

1,317,885.

Specification of Letters Patent.

Patented Oct. 7, 1919.

Application filed March 20, 1919. Serial No. 283,800.

To all whom it may concern:

Be it known that I, PRATT C. MORRIS, a citizen of the United States, residing at Thomasville, in the county of Thomas and State of Georgia, have invented certain new and useful Improvements in Automatic Safety-Springs and Ball-Valve Cocks; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to pet or drain-cocks or valves, and more particularly to drain-cocks or valves for draining or emptying cylinders or chambers containing liquids or fluids and from which the fluid or liquid is drained or discharged at intervals or periods as desired or found necessary, for instance, in auto crank-cases, gas tanks, radiators, or oil, water or other fluid holding vessels. It has for its objects to provide such a pet or drain cock or valve in which the valve-closure element when released from closure holding pressure will unseat itself without sticking to its seat so as to permit the discharge of the contained fluid, liquid or gas, and will instantly close when the discharge from the cylinder or vessel is to be cut-off without danger of being carelessly or negligently left open; which will not accidentally open, and which can be conveniently manipulated even when located in places difficult of access.

To the accomplishment of the foregoing and such other objects as may hereinafter appear the invention consists in the features hereinafter particularly described and then sought to be clearly defined by the claims, reference being had to the accompanying drawing forming a part hereof, and in which—

Figure 1 is a side view of the cock or valve and showing the application of a wrench that may be used for opening it when located in a quite inaccessible place;

Fig. 2, is a horizontal longitudinal section through the cock or valve;

Fig. 3 is an end view of the valve opening stem and side arms; and

Fig. 4 is a plan view of the operating wrench.

In the several figures of the drawing the parts are illustrated on an enlarged scale.

In the drawing the numeral 1 designates the valve-case which may be of any approved form in outline, and has a threaded end or nipple 2 by which it is attached to the cylinder or vessel on which to be used. It has an interior cavity 3 to receive a ball, or closure member 4 which seats against a conical shaped seat 5. Between the ball and the inlet passage 6 is a chamber 7 in which is a spring 8. Within the valve case is a chamber 9 in which fits a spring 10 and which normally holds the ball to its seat so as to close the valve or cock. Between the spring 10 and the ball 4 is a follower 11 which has outwardly extending arms 12 which pass through slots 13 formed in the sides of the casing. To the follower 11 is connected a rod 14 which extends through the head or cap 15 of the casing and is formed with a suitable grip or handle 16 by which a pull may be exerted on the follower to overcome the tension of spring 10 and relieve its pressure against the ball 4 so that the latter may be moved from its seat. The rod 14 may be connected to the follower 11 by a shoulder or head 17 formed at its end and fitting in a socket 18 formed in the follower, or otherwise connected to the follower. The cap or head 15 of the valve casing is preferably made removable for the insertion and removal of the elements contained within the casing, and may be attached to the body of the casing in any suitable manner, for instance by screws 19, or otherwise. The tension of spring 10 is greater than that of spring 8 so as to normally hold the ball against its seat; and the length and tension of spring 8 are such that it will unseat the ball or prevent it from sticking to its seat when the ball is relieved from the seating tension of spring 10.

Opposite sides of the valve casing are formed with shoulders or cheeks 20 having inclined surfaces 21 so that if the cock or valve be located in a quite inaccessible place, a tool or wrench 22 may be used so that its prongs or tangs 23 will bear against the shoulders or cheeks and against the laterally projecting arms 12, and by pressing on the wrench the follower 11 will be moved away from the ball 4 and the latter relieved from the pressure of spring 10 so that the spring 8 may unseat the ball and thus open the pas-

- sage-way of the valve for the escape of fluid or gas therethrough. The valve casing is also formed with a port 24 for the passage of the fluid or gas whose flow is controlled by the ball or closure member of the valve. The ports 24 and 6 may serve as inlet and outlet ports of the valve.
- 5 The ball 4, or flow control member of the valve, may be relieved from the tension of spring 10 so as to open the valve for the passage of fluid or gas, by either pulling on the rod 14, or pressing on the lateral arms 12 with the fingers of the hand or by means of the wrench 22, and when thus relieved 10 the other spring 8 will aid in unseating the ball and prevent it sticking to its seat so that the prompt unseating of the closure member will be effected for the free flow of the liquid or gas.
- 15 20 In a valve formed as described the closure member or ball is held to its seat against accidental displacement by spring pressure; when it is to be opened for the flow of the fluid or gas, the ball is relieved of the major 25 spring pressure by manual manipulation and the minor spring pressure is exerted to promptly unseat the ball and permit the flow of the fluid or gas; and when the manual power on the major spring is released said 30 spring at once exerts its tension to seat the ball and cut off the flow without depending on hand manipulation for cutting off the flow. The valve is adaptable for use in many places and under different conditions 35 and is prompt and efficient in serving the purposes for which designed. Its form may be varied, and its details may be changed without departing from its essential features as endeavored to be expressed in the 40 appended claims.

Having described my invention and set forth its merits what I claim is:

1. The valve comprising a casing having inlet and outlet ports, a movable closure member within the casing, a spring exerting pressure on the closure member to unseat the same, a major spring exerting pressure on 45

said member to normally hold it seated, and means for relieving the pressure of the major spring when the closure member is to be 50 unseated.

2. The valve comprising a valve casing having inlet and outlet ports, a movable closure member within the casing, a spring for normally holding the closure member 55 seated, a spring to exert pressure on the closure member to unseat the same, a follower between the closure member and first mentioned spring, and means for moving said follower to relieve pressure of the first 60 mentioned spring on the closure member.

3. The valve comprising a valve casing having inlet and outlet ports, a movable closure member within the casing, a spring exerting pressure on the closure member to 65 normally hold it seated, a follower between said spring and closure member, arms extending laterally from the follower through the sides of the casing, and shoulders formed on the casing and spaced from said extending 70 arms and against which and said arms a tool may be inserted for moving the follower to relieve the pressure of the spring on the closure member.

4. The valve comprising a casing having 75 an inlet and an outlet port, a movable closure member within the casing, a spring exerting pressure on the closure member to unseat the same, a major spring exerting pressure on said member to normally hold 80 it seated, a follower between said spring and closure member, arms extending laterally from the follower through the sides of the casing, and a stem extending from the follower and through the casing for 85 moving the follower to relieve the pressure of the major spring on the closure member.

In testimony whereof I affix my signature in presence of two witnesses.

PRATT C. MORRIS.
